PEN

Filed Aug. 12, 1936

INVENTOR.
Bert M. Morris
BY *Edwin D. Jones.* ATTORNEY.

UNITED STATES PATENT OFFICE

137,500

Bert M. Morris, Los Angeles, Calif.

5 Claims

My invention relates to pens of that character which constitute part of a pen desk set, and it is a continuation in part of my copending application Serial #64,064, filed February 15, 1936.

5. Pens of this character as heretofore proposed have little ink carrying capacity and hence when in use require frequent dipping to maintain the pen nib supplied with ink for writing.

pen line supplied with ink for writing.

It is a purpose of my invention to provide a pen 10 having an ink reservoir therein which, under the sole action of capillary attraction, can be filled automatically by extending the pen into the dip cup thereby giving to the pen sufficient ink carrying capacity as to permit writing for an ex- 15 tended period without the necessity of redipping

the pen. It is also a purpose of my invention to provide a pen in which the ink reservoir constitutes part of a nib and ink feeder carrier, and wherein the 20 holder of the pen is provided with means for receiving and securely holding the carrier therein so as to permit quick and easy removal thereof without staining the fingers with ink, when the necessity arises for repairing the nib or cleaning

25 necessity arises for repairing the nib, or cleaning the parts of the carrier. What is more important, however, it permits interchanging as a unit of the nib, ink feeder, and reservoir in that fine adjusted relationship one to the other as to insure correct feeding of ink to and proper writing of 30 the nib. Thus, in practise, the elements of the carrier can be assembled, adjusted and sold separately from the pen holder, and used in any holder designed to receive them.

holder designed to removably secure the carrier. I will describe only one form of pen embodying 35 my invention, and will then point out the novel features thereof in claims.

In the accompanying drawing: Fig. 1 is a view showing in side elevation and

40 partly in section one form of pen embodying my invention, with the nib carrier thereof clamped within the holder.

Fig. 2 is a sectional view taken at right angles to Fig. 1 and showing certain parts of the pen disassembled.

Fig. 3 is an enlarged transverse sectional view taken on the line 3-3 of Fig. 1.

Fig. 4 is an enlarged fragmentary sectional view showing those parts of the pen by which the pen 50 chuck is advanced and retracted in the pen barrel, and an enlarged view of the tip of the pen.

Fig. 5 is a transverse sectional view taken on the line 5-5 of Fig. 4.

Fig. 6 is a fragmentary view partly in section showing in the ink reservoir of the pen, another

the Patent Office. The Patent Office is the place where you can get a patent for your invention. It is a government agency that issues patents to inventors. The Patent Office is located in Washington, D.C. It is a large, modern building with many offices and a large lobby. The Patent Office is open to the public, and anyone can visit it to get information about patents. The Patent Office is a great place to visit if you are interested in learning about patents and how they work.

In its present embodiment my pen comprises a holder preferably made of hard rubber and having a barrel 15 and a solid shank 16 provided with a reduced extension 11 fitted rotatably in one end of the barrel. The extension is formed with a reduced neck 18 to which a collar 20 is secured. A collar 19 abuts the shoulder between the neck and extension and is cemented or otherwise fixed to the barrel 15 so as to turn with the latter and to abut the collar 20. This arrangement of collars with respect to the barrel and shank allows relative rotation of the two and yet they are secured against separation so that their confronting ends remain in abutting relation.

As shown in Figs. 1 and 2, the shank 16, the extension 17 and the neck 18 are axially bored and screw threaded as indicated at 21 to receive the screw threaded part 22 of a metal stem 23. This 20 stem at one end is fixed angularly to the solid end of a chuck 24 adapted to be received within the barrel 15.

Thus with those parts of the pen assembled, as described and illustrated in Fig. 1, rotation of the barrel and shank relatively in one direction or the other will cause the chuck to be advanced or retracted in the barrel. In practice, the barrel is held in one hand and the shank rotated with the other to cause the stem to be moved lengthwise in the barrel through cooperation of the threads of the shank and stem, the direction of movement of the stem depending on the direction of rotation of the shank. Were it not for the collars 19 and 20, the shank when rotated on the barrel would tend to separate from the barrel, but the collars prevent this as has been described.

The chuck 24 is formed preferably of hard rubber and made tubular to provide a chamber 25 opening into the outer end of the chuck. Its outer end is exteriorly tapered as indicated at 26; and at diametrically opposed points the chuck is slotted lengthwise as indicated at 27. Such a construction allows the chuck at its open end to be constricted, and the tapered exterior effects such constriction when the chuck is moved to the retracted position shown in Fig. 1. Conversely, by advancing the chuck so as to move the tapered portion out of engagement with the barrel, the chuck end expands to its normal diameter. 50

As it is desirable to prevent rotation of the chuck 24 as it is advanced or retracted within the barrel, I provide lugs or keys 28 positioned at the mouth of the barrel to extend into the slots 27 and thereby secure the barrel and chuck 55

against relative rotation while permitting the chuck to be moved longitudinally in the barrel.

My pen also includes what I term a nib carrier adapted to be received within the chamber 25 of the chuck. This carrier comprises an ink reservoir member 29 preferably made of hard rubber and constructed to provide a solid and rounded nose 30 at one end and a chamber 31 opening to the other end. The diameter of the chamber 31 is such as to permit a feeder member 32 and a nib 33 to be extended and held therein by friction. Movement of the reservoir member inwardly is limited by slightly increasing the outside diameter of the open end of the member to form a shoulder 34.

The feeder member 32 is of conventional form in that it is provided with transverse overflow channels 35 on either edge, and a longitudinal channel 36 on its rounded or nib side extending the length thereof to provide a passage leading into the reservoir chamber 31. Within the chamber 31 may be placed the element 37 shown in Fig. 2, or the multitude of elements 38 shown in Fig. 6, both of which possess that property when in the reservoir chamber of producing a capillary action to fill the reservoir with ink through the channel 36. The element 37 is in the form of a helix and preferably made of hard rubber. The elements 38 are capillary strands of hard rubber or suitable material, and because of their number and intimate relation one to the other they provide a multitude of capillary strands and tubes which greatly accelerate filling of the reservoir with ink.

In operation, the nib carrier can be clamped in the pen holder by first rotating the shank 16 to advance the chuck until the tapered end 26 is clear of the barrel, when the nib carrier can be extended into the chuck and the latter retracted to cause constriction of the end 26 into firm clamping relation to the reservoir member 29. Thus the nib carrier is fixed within the holder for filling and writing.

To fill the pen the feeder member with the nib is extended into a quantity of ink such as that contained in the dip cup of an inkstand or desk set. If allowed to remain therein a relatively short length of time, the capillary action of the channel 36 and the element 37 or elements 38 will cause the reservoir chamber 31 to be filled with ink. It is to be understood that the elements 37 and 38 are not necessary to filling of the reservoir but when used they do accelerate filling, for it will be understood that the capillary action of the channel 36 alone will be sufficient to effect filling of the reservoir but that the process will be slower.

The carrier as a unit can be removed from the holder by advancing the chuck through proper rotation of the shank until the reservoir member is released. Once the carrier is removed its parts can be readily disassembled for cleaning or repair, or an entirely new carrier may be substituted in the holder. Thus my invention lends itself to ready interchangeability of carriers and pen holders, and, in consequence, the separate sale of carriers from the holders, with the added advantage of adapting a carrier having a particular form of nib to a holder having a particular form of design as to shape and color, without disturbing the fine adjustments of the carrier parts necessary to easy writing.

I claim:

1. A pen comprising; a holder having a bar-

rel and a shank rotatable on one end of the barrel; a nib carrier having an ink reservoir; a chuck in the other end of the barrel receiving said carrier and having a constrictable part, said chuck being movable lengthwise in the barrel to occupy one position in which the barrel acts to constrict said part for clamping the nib carrier in the chuck and another position in which the nib carrier is released to allow its removal from the chuck; and an operative connection between the chuck and shank whereby the chuck is moved to occupy one of said positions or the other accordingly as the shank and barrel are rotated relatively in one direction or the other.

2. A pen comprising; a holder having a barrel and a shank rotatable on one end of the barrel; a nib carrier having an ink reservoir; a chuck in the other end of the barrel receiving said carrier and having a constrictable part, said chuck being movable lengthwise in the barrel to occupy one position in which the barrel acts to constrict said part for clamping the nib carrier in the chuck and another position in which the nib carrier is released to allow its removal from the chuck; and coacting means on the chuck and barrel for securing the chuck against rotation.

3. A pen comprising; a holder having a barrel and a shank rotatable on one end of the barrel; a nib carrier having an ink reservoir; a chuck in the other end of the barrel receiving said carrier and having a constrictable part, said chuck being movable lengthwise in the barrel to occupy one position in which the barrel acts to constrict said part for clamping the nib carrier in the chuck and another position in which the nib carrier is released to allow its removal from the chuck; and means within the barrel for securing the barrel and shank against separation at their confronting ends.

4. A pen comprising; a holder having a barrel and a shank rotatable on one end of the barrel; a nib carrier having an ink reservoir; a chuck in the other end of the barrel receiving said carrier and having a constrictable part, said chuck being movable lengthwise in the barrel to occupy one position in which the barrel acts to constrict said part for clamping the nib carrier in the chuck and another position in which the nib carrier is released to allow its removal from the chuck; and coacting means on the chuck and barrel for securing the chuck against rotation; and means within the barrel for securing the barrel and shank against separation at their confronting ends.

5. A pen comprising; a holder having a barrel and a shank rotatable on one end of the barrel; a nib carrier having an ink reservoir; a chuck in the other end of the barrel receiving said carrier and having a tapered and longitudinally slotted neck, said chuck being movable lengthwise in the barrel to occupy one position in which the barrel constricts the neck to clamp the carrier within the chuck and another position in which the barrel disengages the neck to allow the latter to expand and release the carrier; keys on the barrel extending into the slots to prevent rotation of the chuck in the barrel; and an operative connection between the chuck and shank whereby the chuck is moved to one of said positions or the other accordingly as the shank and barrel are rotated relatively in one direction or the other.

BERT M. MORRIS.
